UNITED STATES PATENT OFFICE.

HOWARD M. DUDLEY, OF PHILADELPHIA, PENNSYLVANIA.

DYEING-MACHINE.

1,397,860.

Specification of Letters Patent. Patented Nov. 22, 1921.

Application filed November 21, 1919. Serial No. 339,659.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

My invention relates to dyeing machines and refers particularly to machines suitable for the dyeing of skeins.

One object of my invention is a device whereby skeins of fiber may be treated equally and evenly by a circulating dyeing liquid and whereby the condition of the fiber may be determined without opening the entire apparatus or removing all of the skeins therefrom.

In the modified forms of the device of my invention, shown in the accompanying drawings, similar parts are designated by similar numerals:

Figure 1 is a vertical cross-section of one form of my device.

Fig. 2 is a section through the line 2—2 of Fig. 1.

Fig. 3 is a section through the line 3—3 of Fig. 1 showing the arrangement of parts in the propeller chamber.

Fig. 4 is a section similar to Fig. 3 showing the arrangement of parts in a modification of the propeller chamber.

Fig. 5 is a section on the line 5—5 of Fig. 1.

Fig. 6 is a section on the line 6—6 of Fig. 2.

Fig. 7 is a fragmentary horizontal section of the devices shown in Fig. 8, showing the distributing feed plates.

Fig. 8 is a vertical section of a modification of my device with a propeller at each end thereof, with parts removed.

The particular form of my device, illustrated in the accompanying drawings, comprises a receptacle formed by the sides 10, 11, 12, 13, 14 and 15, the top 16 and the bottom 17. A partition 18, having the two series of openings 19, 19, and 20, 20, extends between the sides 14 and 15, the top 16 and the bottom 17, dividing the receptacle into a propeller chamber 21 and a dyeing chamber 22. Fixedly attached to the interior face of the side 10 is the plate 23, having a lower flange 24. Fixedly attached to the face of the partition 18 is a plate 25 extending between the sides 14 and 15, having a flange

26, a series of openings 27, 27 in alignment with the openings 19, 19 and a series of openings 28, 28 in alignment with the openings 20, 20. Spaced from the side 14 and supported thereto by the brackets 29, 29 is a plate 30 having the flange 31. Spaced from the side 15, and supported thereto by the brackets 32, 32 is a plate 33 having a flange 34. Carried by the flanges 24, 26, 31 and 34 is a foraminous plate 35. The plates 23, 25, 30 and 33 and the foraminous bottom 35, therefore, form a dye box open at the top.

Between the openings 28, 28 of the plate 25, extending between the sides 18 and 33 is a series of plates 36, 36 extending inwardly and then downwardly. A similar series of inwardly and downwardly extended plates 37, 37 is positioned upon the opposite side of the device between the side 14 and the plate 30 and between the corresponding openings in the plate 25. Corresponding inwardly and upwardly extended plates 38, 38 are upon each upper side of the device between the openings 27, 27 of the plate 25. A series of brackets 39, 39 aid in the support of the dye box.

Capable of placement within the dye-box is a foraminous plate 40. Capable of suspension below the foraminous plate 40, is a rod-supporting member comprising the two parallel bars 41, 41 having oppositely opposed openings 42, 42 for the insertion of rods 43, 43.

In order to remove one of the skeins of fiber to determine its dyed condition without removing all of the skeins, oppositely opposed slots 44, 44 are made within the two bars 41, 41. The bar 45 connects the two members 46, 46 fitting in cut-out portions of the foraminous plate 40 and resting upon the plates 30 and 33. The members 46, 46 having the downwardly extended members 47, 47, having oppositely opposed openings 48, 48 carrying the rod 49. The removal of the bar 45 will therefore remove the rod 49 from the dye-box without removing the rods 43, 43.

Directly over the bar 45, and to allow the removal thereof, there is an opening 50, covered by a lid 51, hinged at 52 and capable of being maintained in a closed position by a series of clamps 53, 53.

A series of chains 54, 54 connect the top 16, the foraminous plate 40 and the rod-supporting members so that they may all be removed simultaneously.

The construction of the propeller chamber 21 is shown in Figs. 1 and 3, the inner construction thereof being such as to allow of the free movement of the liquid from the openings 20, 20 upwardly into the openings 19, 19. The member 55, concave upon its one face, carries the elliptical shaped member 58. The member 59 is concave on its inner face and the member 11 is also concave 10 in its upper inner face. Situated within the space formed by the elliptical members 56 and 58 is a liquid propeller 60, fixedly mounted upon the revoluble axis 61, having the pulley 62 capable of revoluble movement. 15 The blades of the propeller 60 are so arranged as to draw liquid from the bottom of the propeller chamber and discharge it inwardly into the upper portion of the propeller chamber.

20 The operation of the device is as follows:—

Skeins 100, 100 are placed upon the rods 43, 43 which are inserted within the openings 42, 42. A skein 100' is placed upon the rod 49 which is inserted within the opening 48. These skeins with the rod-supporting member, the foraminous plate 40 and the top 16 are then lowered into position and the top clamped on, the proper dyeing liquid having been previously introduced into the receptacle. The propeller 60 is then started, which draws the liquid through the spaces between the plates 36, 36 and 37, 37 through the openings 28, 28 and 20, 20 into the lower 30 portion of the propeller chamber, thence upwardly and through the openings 19, 19 and 27, 27 and into and through the spaces between the plates 38, 38. The liquid is thus passed continuously downwardly through the foraminous plate 40, the skeins and the foraminous plate 35, the plates 38, 38 causing an even distribution of liquid into the top of the receptacle and plates 37, 37 and 36, 36 causing it to be taken equally from the 40 various portions of the bottom of the receptacle.

When it is desired to determine the condition of the skeins, the propeller 60 is stopped, the lid 50 opened and the rod 45 withdrawn 50 thus also withdrawing the skein 100' for examination.

The modification shown in Fig. 4 is of the same construction as that previously described except that the propeller 60 is replaced by a pair of propellers 63 and 64, the members 56 and 58 are replaced by the members 65 and 66 and the inwardly extended members 67 and 68 are introduced to allow a free movement of the liquid.

60 The operation of this modification is similar to that described above.

The modification shown in Figs. 7 and 8 is of the same construction as that shown in Figs. 1, 2, 3, 5 and 6 except that it has a 65 propeller chamber and a propeller at each

end. These chambers are similar in construction and similar parts are designated by similar prime numerals. Between the openings 28, 28 of the plate 25 is a series of distributing feed plates 36, 36 extending inwardly and then downwardly, a similar series of plates 70, 70 being between the openings 28, 28 of the plate 23. Corresponding inwardly and upwardly extended plates, similar to plates 38, 38 of Fig. 2, are upon each 75 upper side of the device between the upper openings 27, 27 and 27, 27 of the plates 25 and 33.

In this modification the propellers 60 and 60' draw the liquid between the spaces between the plates 36', 36', 70, 70 into the propeller chambers 21 and 21', thence through the openings 19, 19, 19', 27, 27, 27', 27', into and through the spaces between the upper plates, the liquid thus passing downwardly through the device and the fiber therein.

I do not limit myself to the particular size, shape, number or arrangement of parts described and shown, all of which may be varied without going beyond the scope of my invention as shown, described and claimed.

What I claim is:—

1. In a dyeing machine, in combination, a closed receptacle, a dyeing chamber within the receptacle and spaced therefrom, the dyeing chamber having a foraminous top and a foraminous bottom, a propeller chamber connecting the upper and lower chambers formed by the tops and bottoms of the receptacle and the dyeing chamber, a revoluble propeller within the propeller chamber, a series of openings connecting the side chambers formed by the sides of the dyeing chamber and the receptacle with the lower portion of the propeller chamber and a series of openings connecting the side chambers formed by the sides of the dyeing chamber and the receptacle with the upper portion of the propeller chamber.

2. In a dyeing machine, in combination, a closed receptacle, a dyeing chamber within the receptacle and spaced therefrom, the dyeing chamber having a foraminous top and a foraminous bottom, a propeller chamber connecting the upper and lower chambers formed by the tops and bottoms of the receptacle and the dyeing chamber, a revoluble propeller within the propeller chamber, a series of openings connecting the side chambers formed by the sides of the dyeing chamber and the receptacle with the lower portion of the propeller chamber, a series of openings connecting the side chambers formed by the sides of the dyeing chamber and the receptacle with the upper portion of the propeller chamber.

3. In a dyeing machine, in combination, a closed receptacle, a dyeing chamber within the receptacle and spaced therefrom, the dyeing chamber having a foraminous top and a foraminous bottom, a propeller chamber connecting the upper and lower chambers formed by the tops and bottoms of the receptacle and the dyeing chamber, a revoluble propeller within the propeller chamber, a series of openings connecting the side chambers formed by the sides of the dyeing chamber and the receptacle with the lower portion of the propeller chamber, a series of openings connecting the side chambers formed by the sides of the dyeing chamber and the receptacle with the upper portion of the propeller chamber and a series of chambers within the side chambers connected with the propeller chamber.

3. In a dyeing machine, in combination, a

closed receptacle, a dyeing chamber within the receptacle and spaced therefrom, the dyeing chamber having a foraminous top and a foraminous bottom, a propeller chamber connecting the upper and lower chambers formed by the tops and bottoms of the receptacle and the dyeing chamber, a revolvable propeller within the propeller chamber, a series of openings connecting the side chambers formed by the sides of the dyeing chamber and the receptacle with the lower portion of the propeller chamber, a series of openings connecting the side chambers formed by the sides of the dyeing chamber and the receptacle with the upper portion of the propeller chamber and a series of inwardly and downwardly extended plates from the above openings and within the side chambers. 15

Signed at Chelsea, in the county of Suffolk and State of Massachusetts, this 15th day of November, 1919. 20

HOWARD M. DUDLEY.
